US00D636529S

(12) **United States Design Patent**
Loraing

(10) **Patent No.:** **US D636,529 S**
(45) **Date of Patent:** **** Apr. 19, 2011**

(54) **CONNECTOR FOR OLED LAMP**

(75) Inventor: **Daniela Loraing**, Köln (DE)

(73) Assignee: **Koninklijke Philips Electronics N.V.**,
Eindhoven (NL)

(**) Term: **14 Years**

(21) Appl. No.: **29/357,671**

(22) Filed: **Mar. 16, 2010**

(30) **Foreign Application Priority Data**

Sep. 16, 2009 (EM) 001612268-0002

(51) **LOC (9) Cl.** **26-99**

(57) **CLAIM**

The ornamental design for a connector for OLED lamp, as shown.

DESCRIPTION

FIG. 1 is a perspective view showing my design;
FIG. 2 is a front elevational view thereof;
FIG. 3 is a rear elevational view thereof;
FIG. 4 is a right side elevational view thereof;
FIG. 5 is a left side elevational view thereof;
FIG. 6 is a top plan view thereof; and,
FIG. 7 is a bottom plan view thereof.
